Louis Levine, New York, N. Y.

Application September 6, 1952, Serial No. 21,365

Term of patent 14 years

(Cl. D44—1)

To all whom it may concern:

Be it known that I, Louis Levine, a citizen of the United States and residing in the city, county and State of New York, have invented a new, original, and ornamental Design for a Combined Food Server and Tongs Therefor, of which the following is a specification, reference being had to the accompanying drawing, forming a part thereof.

On the drawing:

Figure 1 is a perspective view of a combined food server and tongs therefor embodying my new design.

Figure 2 is a side view in elevation thereof, the opposite side view being substantially the same.

I claim:

The ornamental design for a combined food server and tongs therefor, substantially as shown and described.

LOUIS LEVINE.
